UNITED STATES PATENT OFFICE.

EDGAR STEDMAN KING, OF OSGOOD, INDIANA.

AUTOMATIC FUEL CUT-OFF.

1,399,967.

Specification of Letters Patent. Patented Dec. 13, 1921.

Application filed October 8, 1920. Serial No. 415,684.

To all whom it may concern:

Be it known that I, EDGAR STEDMAN KING, a citizen of the United States, and a resident of Osgood, in the county of Ripley and State of Indiana, have invented certain new and useful Improvements in Automatic Fuel Cut-Offs, of which the following is a specification.

The present invention relates to an automatic fuel cutoff for internal combustion engines or the like.

The object of the invention is to provide an automatic fuel cutoff of this character which is controlled by the pressure in the lubricating system of the engine, which is effective to cut off the supply of fuel to the engine when the pressure in the lubricating system falls below the point at which a complete and efficient circulation of the lubricant is insured or dangerously exceeds the point of safe operation and which is of extremely simple and durable construction, reliable in operation and easy and inexpensive to manufacture.

Other objects and advantages of the invention reside in certain novel features of construction, combination and arrangement of parts, as will be hereinafter more fully described and particularly pointed out in the appended claims, reference being had to the accompanying drawings forming part of this specification, and in which:

Figure 1 is a transverse vertical sectional view of the invention, parts being shown in elevation for the sake of illustration;

Fig. 2 is a transverse horizontal sectional view on line 2—2 of Fig. 1, illustrating the construction common to all embodiments of the invention;

Fig. 3 is a transverse vertical sectional view of a modified form, parts being shown in elevation for the sake of illustration;

Fig. 4 is a similar view of another modified form; and

Fig. 5 is a diagrammatic view, illustrating diagrammatically the manner in which the invention is associated with an internal combustion engine.

Referring to the drawings, and especially to Fig. 5, it will be seen the invention contemplates an internal combustion engine of any conventional or standard type and designated generally at I. The engine includes as usual a carbureter C and a lubricating system, designated diagrammatically at L which embodies a pump designated at P.

A fuel tank G is provided, and is adapted to supply fuel to the carbureter C through the pipe line O. The automatic cutoff which constitutes my invention is designated generally at A, and as shown in the drawings is incorporated in the pipe line O which leads from the fuel reservoir to the carbureter.

This automatic cutoff in all embodiments of the invention includes a cylinder 10 having its ends provided with upper and lower caps, designated at 11 and 12, respectively and suitably secured to the cylinder. The upper cap 11 is provided with a centrally disposed and internally threaded opening 13 which communicates at its inner end with an axially aligned but reduced opening 14 leading into the interior of the cylinder 10. A section O¹ of the pipe fuel line O is secured to the cap 11 by threaded engagement with the opening 13, as clearly shown in Figs. 1, 3 and 4. Intermediate its ends the cylinder is provided with a lateral opening 15 which communicates with another section O² of the pipe line O which also has threaded engagement with the outer end of the opening 15. The opening 15 constitutes a discharge outlet for the fuel.

A piston, designated generally at 16, is slidably mounted within the interior of the cylinder 10. The piston includes a lower solid head 17 which is slidable in the lower portion of the cylinder and an upper hollow head 18 having its upper end open and which is slidable in the upper portion of the cylinder. Intermediate the heads 17 and 18 an annular groove 19 is cut in the periphery of the piston thus forming a neck connecting the upper and lower heads. The upper head 18 is provided with a circular series of openings 20 which extend from the interior thereof to the annular groove 19.

In all of the embodiments of the invention, spring means is interposed between the upper head 18 of the piston 16 and the cap 11.

In the form of my invention shown in Fig. 1, this spring means comprises a single coil spring 21 abutting at its opposite ends the upper head 18 of the piston 16 and the cap 11, respectively. The coil spring 21 is arranged in the hollow head 18, as shown in Fig. 1. It is of such strength as to limit the upward movement of the piston 16 of the cylinder to the position shown in Fig. 1.

In the form of my invention shown in Fig.

3, the spring means consists of two coil springs, designated at 21^a and 21^b, respectively. The spring 21^a consists of a relatively long and relatively light coil spring 5 which is actively engaged with the upper head 18 of the piston 16 in all of its operative positions. The spring 21^b consists of a relatively short and heavy coil spring which is arranged within the coil spring 21^a 10 and which normally has no effect upon the piston 16, only coming into action when the piston 16 reaches the position shown in Fig. 3 with the annular groove 19 alined with the discharge outlet 15. At this time the coil 15 spring 21^b supplements the action of the coil spring 21^a in resisting upward movement of the piston 16 in the cylinder, as will be hereinafter more fully described.

In the form of my invention shown in Fig. 20 4 the coil spring is substantially the same as the coil spring 21 of Fig. 1 and is designated at 21^c and is similar in its relations and in its action to the other elements of the cutoff.

25 In all forms of the invention, the lower cap 12 of each cylinder 10 is provided with a centrally disposed integrally threaded opening 12^a and is connected by means of a short pipe connection L' and a T-connection 30 L² with the oil circuit or lubricating system L. This arrangement exposes the lower head 17 of the piston 16 to the oil pressure in the lubricating system, and this pressure when it is normal forces the piston 16 up 35 into the cylinder to the position shown in Figs. 1, 3 and 4, with the annular groove or neck thereof alined with the lateral opening 15 of the cylinder thus providing for a continuous flow of fuel from the tank C 40 through the section O¹ of the pipe line O, the opening 14, the upper portion of the cylinder 10, the interior of the hollow piston 18, the openings 20, annular groove 19, the opening 15 and the section O² of the pipe 45 line O to the carbureter C. If, however, the pressure in the lubricating system falls below the point to insure proper circulation the piston 16 under the action of the spring means drops down in the cylinder until the 50 outer solid wall of the hollow piston completely covers the lateral opening 15 and cuts off the flow of fuel to the carbureter of the engine and stops the engine until the conditions in the lubricating system have been 55 remedied. In addition to this action in the embodiment of my invention shown in Fig. 3, if the pressure in the lubricating system increases to such an excessive and dangerous degree as to forecast serious injury, the 60 pressure forces the piston 16 up in the cylinder past the position shown in Fig. 3 and against the action of both the springs 21^a and 21^b until the solid head 17 covers the discharge outlet 15 and cuts off the flow of 65 fuel to the engine.

In the form of my invention shown in Fig. 4, auxiliary means is provided for cutting off the flow of fuel. As shown in the drawings in this form of the invention the cap 11 is elongated and has provided therein 70 an auxiliary valve cavity 22 having in its lower portion a conical valve seat 23 with which the conical valve head 24 of the auxiliary valve coöperates. The conical valve head 24 is carried at the upper end of the 75 valve stem 25 which is secured at its lower end to the upper piston head 18. It is apparent that when the engine is idle and the piston 16 has dropped down in the cylinder under the action of the spring means, the 80 conical valve head 24 will coöperate with the conical valve seat 23 to cut off the flow of fuel in conjunction with the action of the head 18 of the piston.

In order to provide for starting when 85 ordinarily there is no pressure in the lubricating system, a bypass from the pipe section O' to the pipe section O² is provided. This bypass is preferably cast integral with the cylinder 10 and has therein an opening 90 28 which extends from the opening 14 to the opening 15. The portion of the bypass surrounding the opening 28 and adjacent the opening 14 is provided with a valve seat 29 for the needle valve 30. The needle 95 valve has its shank threaded, as usual and as indicated at 30^a, and is provided with a stuffing box 31. It is obvious that when the needle valve is turned so as to be removed from its seat 29 and the fuel may 100 flow freely from the pipe section O' to the opening 14 and thence through the opening 28 to the opening 15 which is what occurs when the engine is started. After the engine has been started the needle valve is 105 turned to engage its seat and cut off the flow through the bypass and at this time the automatic cutoff is operative to shut off the supply of fuel should the conditions in the 110 lubricating system become dangerous.

It is to be noted that all of the working parts of the cutoff are inclosed in a dust-proof and water-proof casing and operate in oil and thus are not affected by the weather or other elemental conditions and 115 are susceptible of efficiently operating on a very low pressure. The invention is so well organized and it is of such simple and compact construction that it can be advantageously associated with the standard internal combustion engine without interfering with the other mechanical equipment thereof and the jolts and jars to which it may be subjected do not materially affect its operation. It thus provides for the cutting off 120 of the fuel not only where the engine or the elements thereof are in danger because of insufficient lubrication or the lubricating system or its elements are in danger because of excessive lubrication but it also 125 130

prevents waste of fuel and the ingress of foreign matter into the fuel supply system when the engine is not in operation.

It is to be understood in connection with the operation of the spring means that in the forms of the invention shown in Figs. 1 and 4 the strength of each coil spring is such that it limits the upward movement of the piston to the position shown in Figs. 1 and 4 and that in this form of the invention the piston is preferably not adapted to cut off the supply of fuel under the action of excessive oil pressure. In the embodiment of the invention shown in Fig. 4 the relatively long and light coil spring 21^a serves only to balance the normal oil pressure and to force the piston downwardly when the oil pressure falls below the point at which safe and efficient circulation of the oil is maintained but it does not limit the upward movement of the piston in the cylinder nor does the combined action of the coil springs 21^a and 21^b. The combined action of these coil springs however is effective to prevent upward movement of the piston in the cylinder to the point at which the annular groove aligns with the discharge outlet for the fuel at all pressures excepting an exceedingly high and dangerous pressure and under such circumstances these coil springs are compressed to permit the lower solid head of the piston to cover the discharge outlet and cut off the supply of fuel.

I claim:

1. In a device of the character described, in combination with an internal combustion engine having fuel supply and a lubricating system in which the lubricant is circulated under pressure, an automatic fuel cutoff incorporated in the fuel supply and controlled by the pressure of the lubricant and consisting of a cylinder having its upper end in communication with the fuel supply and having a lateral discharge outlet for the fuel intermediate its ends and having its lower end in communication with the lubricating system, a piston slidably mounted in said cylinder having a lower solid head exposed to the pressure of the lubricating system, an upper hollow head having its upper end open, said piston being provided intermediate the upper and lower heads with an annular groove in its periphery and a plurality of openings extending from the interior of the hollow head to the annular groove, a coil spring arranged in the upper end of the cylinder and engaging the upper head of the piston whereby the normal lubricant pressure when the engine is running balances the coil spring to align the annular groove with the lateral discharge outlet and permit a free flow of fuel, a bypass around said cylinder for

starting the engine, and a needle valve controlling said bypass.

2. In a device of the character described, in combination with an internal combustion engine having a fuel supply and a lubricating system in which the lubricant is circulated under pressure, an automatic fuel cutoff incorporated in the fuel supply and controlled by the pressure of the lubricant and consisting of a cylinder having its upper end in communication with the fuel supply and having a lateral discharge outlet for the fuel intermediate its ends and having its lower end in communication with the lubricating system, a piston slidably mounted in said cylinder having a lower solid head exposed to the pressure of the lubricating system, an upper hollow head having its upper end open, said piston being provided intermediate the upper and lower heads with an annular groove in its periphery and a plurality of openings extending from the interior of the hollow head to the annular groove, and a coil spring arranged in the upper end of the cylinder and engaging the upper head of the piston whereby the normal lubricant pressure when the engine is running balances the coil spring to align the annular groove with the lateral discharge outlet and permit a free flow of fuel.

3. In a device of the character described, in combination with an internal combustion engine having fuel supply and a lubricating system in which the lubricant is circulated under pressure, an automatic fuel cutoff incorporated in the fuel supply and controlled by the pressure of the lubricant and consisting of a cylinder having its upper end in communication with the fuel supply and having a lateral discharge outlet for the fuel intermediate its ends and having its lower end in communication with the lubricating system, and a piston slidably mounted in said cylinder having a lower solid head exposed to the pressure of the lubricating system, an upper hollow head having its upper end open, said piston being provided intermediate the upper and lower heads with an annular groove in its periphery and a plurality of openings extending from the interior of the hollow head to the annular groove.

4. In an automatic fuel cutoff of the character described for use in internal combustion engines having a lubricating system in which the lubricant circulates under pressure, a cylinder, a piston slidably mounted in said cylinder having an upper hollow head having its upper end open and a lower solid head exposed to the pressure of the lubricant, said piston being provided with an annular groove intermediate said heads and a plurality of openings affording com-

- munication between the interior of the hollow head and the annular groove and a coil spring bearing against the hollow head of said piston.
5. An automatic fuel cutoff of the character described for internal combustion engines having a fuel supply including a fuel line and a lubricating system in which the lubricant is circulated under pressure including a cylinder incorporated in the fuel supply line, a piston slidably mounted in the cylinder and having an upper head and a lower head, said piston being provided with an annular groove intermediate said heads, the lower head of said piston being exposed to the pressure of the lubricating system, and the upper head having an opening therethrough to provide for the control of the fuel, and a coil spring bearing against the upper head of said piston and balancing the normal lubricant pressure.
6. An automatic fuel cutoff of the character described for internal combustion engines having a fuel supply including a fuel line and a lubricating system in which the lubricant is circulated under pressure including a cylinder incorporated in the fuel supply line, and a piston slidably mounted in the cylinder and having an upper head and a lower head, said piston being provided with an annular groove intermediate said heads, the lower head of said piston being exposed to the pressure of the lubricating system, and the upper head having an opening therethrough to provide for the control of the fuel.
7. An automatic fuel cutoff of the character described for internal combustion engines having a fuel supply including a fuel line and a lubricating system in which the lubricant is circulated under pressure including a cylinder incorporated in the fuel supply line and having an inlet for the fuel at its upper end and a lateral discharge outlet therefor intermediate its ends, a piston slidably mounted in the cylinder and having an upper hollow head provided with an upper open end and a lower solid head exposed to the pressure of the lubricating system, said piston being provided intermediate said upper and lower heads with an annular groove and having a plurality of openings affording communication between the upper hollow head and the annular groove, and a coil spring bearing against the upper head of said piston and for balancing the normal lubricant pressure to retain the lateral groove alined with the discharge outlet.
8. An automatic fuel cutoff of the character described for internal combustion engines having a fuel supply including a fuel line and a lubricating system in which the lubricant is circulated under pressure including a cylinder incorporated in the fuel supply line and having an inlet for the fuel at its upper end and a lateral discharge outlet therefor intermediate its ends, a piston slidably mounted in the cylinder and having an upper hollow head provided with an upper open end and a lower solid head exposed to the pressure of the lubricating system, said piston being provided intermediate said upper and lower heads with an annular groove and having a plurality of openings affording communication between the upper hollow head and the annular groove, and a coil spring bearing against the upper head of said piston and for balancing the normal lubricant pressure to retain the lateral groove alined with the discharge outlet.
9. In an automatic fuel cutoff of the character described for use in internal combustion engines having a lubricating system in which the lubricant circulates under pressure, means actuated by the pressure of the lubricant for controlling the supply of fuel including a piston having a head exposed to the pressure of the lubricant, and spring means operatively engaging with the opposite head of the piston consisting of a relatively elongated and light coil spring and a relatively short and heavy coil spring arranged within said first-mentioned coil spring.
10. In an automatic fuel cutoff of the character described for use in internal combustion engines having a lubricating system in which the lubricant circulates under pressure, means actuated by the pressure of the lubricant for controlling the supply of fuel including a piston having a head exposed to the pressure of the lubricant and a head opposite said exposed head and a plurality of coil springs adapted to successively operate against said opposite end, all as and for the purposes set forth.

EDGAR STEDMAN KING.
